UNITED STATES PATENT OFFICE.

DAVID MAXWELL, OF DETROIT, MICHIGAN.

TRUSS-REINFORCE FOR CONCRETE.

No. 859,311.

Specification of Letters Patent.

Patented July 9, 1907.

Application filed April 6, 1906. Serial No. 310,259.

To all whom it may concern:

Be it known that I, DAVID MAXWELL, of Detroit, Wayne county, Michigan, have invented a new and useful Truss-Reinforce for Concrete, of which the following is a full, clear, and exact description, reference being had to the accompanying drawings, forming part of this specification, in which—

Figure 1 is a side elevation of my improved reinforce; Fig. 2 is a cross-section of the blank from which 10 it is formed; and Fig. 3 is a cross-section on the line III—III of Fig. 1.

My invention relates to metal reinforcing for concrete beams and structures, and is designed to provide a reinforce which may be cheaply and simply made, 15 and which will give prompt resistance to the compressive tensile and shearing stresses.

In the drawings, in which I show a preferred form of my invention, Fig. 2 represents in cross-section the preferred form of blank. This blank consists of 20 the rolled section having a web 2, a square top chord 3 and a diamond-shaped lower tension chord 4. This rolled section is slotted on oblique lines extending upwardly and outwardly from the lower central portion, the inclination being opposite on opposite sides 25 of the center. The slotted portions are then bent into oppositely directed flanges 5 and 6, thus giving a Z-shape to each brace, as shown in Figs. 1 and 3. The central portion of the web is preferably cut out in triangular form as shown at 7. As the horizontal 30 lines of cut are parallel with the top and bottom chords the bending outward of the flanges will cause their alternate upper and lower ends to extend at inclines, as shown at 8 and 9. The slitting may be carried out by rolls or presses, and the bending may be formed 35 by presses or any other desirable manner.

The advantages of my invention result from the great strength of the concrete beam, in which this reinforce is embedded. The braces extend upwardly and outward in opposite directions on opposite sides of 40 the center, and transmit the strains from one chord to the other. The upper chord is of course in compression while the lower chord is in tension.

Many changes may be made in the size and form of the rolled shape, the blank may be in the form of a 45 plain sheet or plate or a plate provided with an upper enlargement or a lower enlargement only, and many

other changes may be made without departing from my invention.

I claim:

1. A metallic reinforce for concrete structures in the 50 form of a braced truss, said truss consisting of a lower chord, an upper chord, and oblique members or braces connecting the upper and lower chords and having flanges bent laterally in opposite directions; substantially as described. 55

2. A metallic reinforce for concrete structures in the form of a braced truss, having a thickened lower edge portion constituting a lower chord and provided with braces extending obliquely therefrom, said braces having oppositely bent laterally extending flanges, the braces at 60 opposite sides of the central portion of the truss being inclined in opposite directions; substantially as described.

3. A metallic reinforce, consisting of a truss structure having upper and lower chords and braces connecting said chords, said braces having oppositely bent laterally 65 extending flanges; substantially as described.

4. A metallic reinforce formed from a plate having a lower thickened chord portion, the web of said plate being cut on opposite inclines and the braces thus formed having oppositely projecting flanges; substantially as 70 described.

5. A metallic reinforce comprising a plate having thickened upper and lower chord portions, the web of the plate having oppositely inclined cuts on opposite sides forming braces, said braces having oppositely directed 75 flanges; substantially as described.

6. A metallic reinforce comprising a plate having thickened upper and lower chord portions, the web of the plate having oppositely inclined cuts on opposite sides forming braces, said braces having oppositely directed 80 flanges, the central portion of the web being open; substantially as described.

7. A metallic reinforce, consisting of a truss formed of an integral plate whose upper and lower edge portions constitute the upper and lower chords of the truss, the 85 intermediate portion of the plate having therein a plurality of oblique slits, and the metal between the slits being shaped to form braces having oppositely directed laterally extending flanges; substantially as described.

8. A metallic reinforce consisting of an integral plate 90 formed with a plurality of oblique slits inclined in opposite directions at each side of the center of the reinforce, the slits at one side of the center being inclined reversely to those at the other side, and the metal between each adjacent pair of slits being shaped into flanged braces 95 connected at top and bottom by the integral edge portions of the plate; substantially as described.

In testimony whereof, I have hereunto set my hand.

DAVID MAXWELL.
